UNITED STATES PATENT OFFICE.

HEINRICH BANGERT, OF DUSSELDORF, GERMANY.

FURNACE.

Application filed June 9, 1926. Serial No. 114,660.

The invention relates to continuous heating furnaces of the type in which a furnace is provided at one end with a charging and at its other end with a discharging opening, the material to be heated being placed in the furnace through its charging opening and progressively moved through the furnace toward and to its discharging opening, and the material being heated while in and so moved through the furnace. While the invention may be used in continuous furnaces for heating different kinds of material, it is particularly applicable to furnaces for heating sheet bars for rolling into sheet metal.

An object of the invention is to provide a furnace of the type explained in which provision is made for introducing fuel gas at or adjacent to the charging end of the furnace, and for producing maximum heating effect at or adjacent to the discharge end, the heating effect progressively diminishing from the discharging to the charging end of the furnace.

A further object is to provide a furnace in which fuel gas is introduced at or adjacent to the charging end of the furnace, and in which provision is made for heating auxiliary air for combustion, which air is mixed with the fuel gas at or adjacent to the discharge end of the furnace to effect maximum heating in that region.

The invention is illustrated in the accompanying drawings, of which Fig. 1 is a vertical central sectional view through a continuous heating furnace; Fig. 2 a transverse vertical sectional view taken on the line II-II, Fig. 1; Fig. 3 a horizontal sectional view taken on the line III-III, Fig. 1; and Figs. 4 and 5 vertical sectional views similar to Fig. 1 showing modifications of construction.

Having reference first to the embodiment of the invention illustrated in Figs. 1, 2 and 3, there is shown a furnace having end walls 1 and 2, side walls 3 and 4, a top 14, and a bottom 5, the bottom being provided with suitable supports or skids 6 for supporting sheet bars or other blanks to be heated, which blanks are placed in the furnace through a charging opening 8 in its end wall 1 and removed from the furnace through a discharging opening 9 in its end wall 2. These furnace openings are normally closed by suitable blocks 10 and 11, the construction and operation of which are well known to those skilled in the art. Side wall 4 is provided with a

fuel gas inlet 12 which may, and preferably does, lead from a gas producer arranged adjacent to this inlet, although it will be understood that fuel gas may be supplied from a source otherwise located.

Between the top 14 and bottom 5 of the furnace there is a horizontally disposed arched wall or muffle 15 extending from one side wall to the other and from front wall 1 towards rear wall 2. This wall 15 forms with side walls 3 and 4 above it, and with the top of the furnace, a passageway 16 for the fuel gas which enters inlet 12. When this fuel gas comes from a gas producer arranged adjacent to the charging end of the furnace it is heated and preferably in a state of partial combustion, although as far as concern some features of the invention no further combustion need take place. It flows towards the discharging end of the furnace in the direction indicated by arrows 17, and at the end of wall 15 it turns downwardly and flows toward the charging end of the furnace, as also indicated by these arrows.

At the end of wall 15, where the fuel gas turns downwardly, a supply of auxiliary air is mixed with the fuel gas so that the maximum heating effect of the gas is in the zone or region of the discharge end of the furnace. This auxiliary air may be supplied through passageways 20 formed in wall 15, the passageways having outlets at the end of this wall and having inlets communicating with an air supply duct 21 in end wall 1 at the charging end of the furnace. Duct 21 may lead from a recuperator, or from any other source of air supply, the air being either at atmospheric temperature or being preliminarily heated. As the auxiliary air flows through passageways 20 in wall 15 it becomes heated so that when it is mixed with the fuel gas at the end of the wall a maximum heating effect is produced.

So that the products of combustion as they flow from the zone of maximum heating effect adjacent to the discharging end of the furnace may uniformly heat all portions of blanks 7, skids 6 are preferably elevated above furnace bottom 5 by means of refractory ribs 22. By so supporting the blanks above the furnace bottom, passageways for the products of combustion are formed below and at the sides of the blanks as well as above them. At the charging end of the furnace, wall 5 is provided with a port 25 through which the products of combustion

flow downwardly into a passageway 26 which communicates through a port 27 with a passageway 28 leading either directly to a stack or to and through a recuperator for 5 preliminarily heating air or fuel gas.

In the embodiment of the invention illustrated in Fig. 4, the furnace is constructed the same as shown in Figs. 1, 2 and 3, except that in the Fig. 4 form wall 15^a is not 10 provided with passageways for the introduction and preliminary heating of auxiliary air. In lieu of this, auxiliary air is supplied through a series of passages 30 arranged in the furnace top 14^a and leading 15 from an air duct 31 arranged above the top of the furnace. Duct 31 may lead from any suitable air supply, as for example from a recuperator in which the air is preliminarily heated. Passages 30 so direct the auxiliary 20 air into the fuel gas entering the furnace through inlet 12^a that the auxiliary air meets the fuel gas adjacent to the end of wall 15^a to produce maximum heating effect in the discharge region of the furnace.

25 In the embodiment of the invention illustrated in Fig. 5, muffle wall 15^b is provided adjacent to its end with a plurality of vertically disposed passages 35 through which fuel gas may flow downwardly through the 30 wall. In this embodiment of the invention, auxiliary air is supplied to the furnace heating chamber through passages 36 in the furnace top 14^b adjacent to the rear furnace wall 2^b. Passages 36 lead from an air duct 37, which in turn may lead from a recuperator or any other source of air supply, and control of air from duct 37 through passages 36 may be effected by suitable dampers 38.

It is characteristic of each of the several 40 embodiments of the invention that fuel gas enters the furnace through an inlet at the charging end, that it then flows towards the discharging end of the furnace where it is supplied with auxiliary air to effect maximum heating in the region of the discharge 45 end of the furnace, and that the products of combustion then flow towards the charging end of the furnace on all sides of the blanks being heated. In this way the hottest 50 test blanks are subjected to the maximum effect and the cooler blanks adjacent to the charging end of the furnace are heated by products of combustion which are not as hot as at the zone of maximum heating.

55 According to the provisions of the patent statutes, I have explained the principle and operation of my invention, and have illustrated and described several embodiments of it. However, I desire to have it understood 60 that, within the scope of the appended

claims, the invention may be practiced by other forms of construction than those particularly illustrated and described.

I claim as my invention:

1. A continuous heating furnace having a 65 charging and a discharging end and a top and bottom, a wall below the furnace top extending from the charging toward the discharging end of the furnace, a fuel gas inlet adjacent to the charging end of the 70 furnace and above said wall, and passageways extending longitudinally through said wall for supplying heated auxiliary air to the fuel gas adjacent to the discharging end of the furnace. 75

2. A continuous heating furnace having a charging and a discharging end and a top and bottom, a wall below the furnace top extending from the charging toward the discharging end of the furnace, a fuel gas inlet adjacent to the charging end of the furnace and above said wall, and an outlet for 80 products of combustion below said wall and adjacent to the charging end of the furnace.

3. A continuous heating furnace having a 85 charging and a discharging end and a top and bottom, a wall below the furnace top extending from the charging toward the discharging end of the furnace, a fuel gas inlet adjacent to the charging end of the furnace and above said wall, an outlet for products 90 of combustion below said wall and adjacent to the charging end of the furnace, and blank-supporting skids extending longitudinally of the furnace elevated above the furnace bottom to form passages for products of combustion above, below and at the ends of blanks supported on the skids. 95

4. A continuous heating furnace having a 100 charging and a discharging end and a top and bottom, a wall below the furnace top extending from the charging toward the discharging end of the furnace, a fuel gas inlet adjacent to the charging end of the furnace and above said wall, passageways extending 105 longitudinally through said wall for supplying heated auxiliary air to the fuel gas adjacent to the discharging end of the furnace, an outlet for products of combustion below said wall and adjacent to the charging end 110 of the furnace, and blank-supporting skids extending longitudinally of the furnace elevated above the furnace bottom to form passages for products of combustion above, below and at the ends of blanks supported 115 on the skids.

In testimony whereof, I hereunto sign my name.

HEINRICH BANGERT.
